PIPE WRAPPING MACHINE

Herman Kramer, Tulsa, Okla., assignor to The
Ruberoid Co., New York, N. Y., a corporation
of New Jersey

Application May 7, 1938, Serial No. 206,550

4 Claims. (Cl. 242—11)

This invention relates to a pipe wrapping machine, and more particularly to apparatus for winding sheet material helically around a stationary pipe.

The machine is especially adapted for applying, in situ, a protective wrapping around pipes such as are used in oil or gas transmission pipe lines, although it may be used for other purposes.

The principal object of the invention is to provide a manually operable machine in which the angular setting of the roll of wrapping material governs the extent of the lap and the pitch of the forward movement.

Other objects are to provide a machine that is light in weight; that can be conveniently transported and handled, consisting of few parts which may be readily set up in the field as required to wind pipes; and that can be easily operated manually by a single operator.

Further objects and advantages of the machine will appear more fully from the following description thereof, reference being had to the accompanying drawings, in which:

Figure 1 is a top plan view of the wrapping machine in position on a pipe;

Fig. 2 is a side view thereof;

Fig. 3 is a vertical section on the line 3—3 of Fig. 2, the direction of rotation of the machine being indicated by the dotted line position;

Fig. 4 is an end view of the machine, looking from the right hand side of Figure 1;

Fig. 5 is an end view of the roll of wrapping material and the tensioning device, looking in the direction of the arrow 5 in Figure 1;

Fig. 6 is a side elevation of the parts shown in Fig. 5, viewed in the direction of the arrow 6; and

Fig. 7 is a detail view showing a manner of adjusting the angularity of the subsidiary frame.

The main frame structure of the machine consists of two parts, namely: an upper and a lower part, indicated generally by the reference characters 10 and 11, respectively. In setting up the machine, the upper frame part 10 is placed upon the pipe 12, and the lower part 11 is moved into position to embrace the pipe, whereupon the two parts are detachably secured together as by means of the pins or bolts 13.

The upper frame part 10 comprises two parallel longitudinal members 14—14 connected at their rear ends by a cross-piece 15 having downwardly projecting flanges 16. The forward portion of one of the members 14 is bent out of line as shown. A subsidiary frame 17, for supporting the roll 18 of wrapping material, extends at an angle across the forward end of the main frame

part 10, as best seen in Figure 1. The subsidiary frame comprises two parallel side members 19—19, and end members 20. The angular setting of the subsidiary frame may be varied to regulate the pitch and the lap of the winding of wrapping material. One means of effecting such adjustment is shown in Fig. 7, wherein the subsidiary frame 17 is pivotally mounted on the main frame part 10 by means of a bolt 21 and is fastened in adjusted position by passing the bolt 22 selectively through one of the holes 23. Mounted on the side members 19 are upright members 24 having vertical slots 25 for the reception of the spindle or rod 26 that carries the roll of wrapping material. The frame part 10 15 may be provided with a handle bar 27 for convenience in handling.

The lower frame part 11, best seen in Figs. 3 and 4, consists of a substantially U-shaped structure comprising horizontal members 28 and vertical members 29, connected by angle members 30. Triangular blocks 31, preferably wooden blocks, are fastened in two lower corners of the frame part 11 for the purpose hereinafter described.

The roll 18 of paper, felt, or like wrapping material is supported on the spindle 26. Two cones 32 are slipped over the spindle and enter into the ends of the core of the roll 18. The roll with the spindle in place is inserted between the upright members 24, with the ends of the spindle riding in and extending outwardly beyond the slots 25. The members 24 bear on the sides of the roll 18 and prevent it from shifting or coning during unwinding.

Means are provided for pressing the roll 18 down against the pipe with the proper tension required as the wrapping material is being unwound. These means, in the particular embodiment shown, comprise a pair of slightly curved spring arms 33—33, pivotally connected at their rear ends to a cross rod 34 supported on one end of the subsidiary frame 17 and connected at their forward ends by the handle bar 35. 36 is a cross-piece secured to the spring arms and having an opening through which the toothed rack 37 extends. The lower end of the rack, as seen in Fig. 5, is pivotally secured at 38 to the forward end of the subsidiary frame 17. A leaf spring 39, fastened to the cross-piece 36, bears against the back of the rack 37 and causes engagement of the teeth with an edge of the opening. It will be noted that the spring arms 33 pass over the projecting ends of the spindle 26. As the material is being unwound from the roll 18, the

spring arms are moved gradually downward to supply the required tension. This is continued until all or substantially all of the material wound on the roll has been used. When a fresh roll is inserted, the spring arms are disconnected from the rack and are thrown back.

5 A plurality of handles 40, in the present instance four, are provided for rotating the machine bodily around the pipe. 41 is a flat spring 10 attached to the under-surface of one of the side members of the subsidiary frame 17 and bearing with light pressure on the pipe 12.

In operation, the pipe may be temporarily supported on blocks or horses above or adjacent to 15 the trench in which it is to be laid, and the machine is set up in position on the pipe. In setting up the machine, all that is necessary is to couple together the two parts of the main frame, and to insert a roll of wrapping material in the 20 subsidiary frame. The operator, standing in position at the front end of the machine, turns the frame together with the roll of wrapping material bodily around the pipe by means of the handle levers 40. The roll of wrapping material bears on the pipe and the angularity of its 25 setting causes the machine to move forwardly along the pipe as the frame is rotated, thus unwinding the material from the roll and winding it helically around the pipe with the proper over- 30 lap, as shown in Figs. 1 and 2. The wrapping material generally consists of a web of saturated felt. As the material is unwound onto the pipe, the tension on the roll is adjusted by means of a take-up device which, in the present instance, 35 comprises the rack 37. I have found that only very little tension on the roll or a slight frictional drag on the material is necessary to effect a tight and uniform wrap. During the travel of the frame, the smoother blocks 31 bear on the wrapping material and serve to smooth the winding, 40 to press down and seal the lap, as well as to center the frame on the pipe. The blocks are held firmly in contact with the wrapping material by means of the tensioning device and the spring 45 41. The pipe is coated with a bituminous composition before the wrapping material is applied thereto, and, if desired, an outer coating of similar substance may be applied after the pipe has been wrapped.

50 It will be noted that the roll 18 of wrapping material is mounted on the frame with its axis extending at an angle to the axis of the pipe.

This angular relationship governs the pitch of the forward movement of the machine and causes the wrapping material to be wrapped around the pipe with a uniform lap. Both the pitch and the lap may be regulated by varying the angular setting of the roll of wrapping material.

Various modifications in the details of construction illustrated and described may be resorted to without departing from the scope or spirit of the invention as defined in the appended 10 claims.

What I claim is:

1. A pipe wrapping machine comprising a frame mountable upon and rotatable about a pipe to be wrapped, a roll of wrapping material 15 mounted upon and bodily rotatable with the frame, said roll bearing on the pipe and having its axis set at an angle to the axis of the pipe, and means mounted on the frame to ride over and smooth the wrapping material after it has 20 been wound around the pipe.

2. A pipe wrapping machine comprising a frame mountable upon and rotatable about a pipe to be wrapped, a roll of wrapping material 25 mounted upon and bodily rotatable with the frame, said roll bearing on the pipe and having its axis set at an angle to the axis of the pipe, and smoother blocks immovably mounted on the frame to ride over and smooth the wrapping material after it has been wound around the pipe. 30

3. A pipe wrapping machine comprising a frame mountable upon and rotatable about a pipe to be wrapped, a roll of wrapping material 35 mounted upon and bodily rotatable with the frame, said roll bearing on the pipe and having its axis set at an angle to the axis of the pipe, means mounted on the frame to ride over and smooth the wrapping material after it has been wound around the pipe, and tensioning means acting on the roll to maintain it in contact with 40 the pipe as the diameter of the roll decreases.

4. In a pipe wrapping machine, a frame adapted to be mounted on and rotated about a pipe to be wrapped, supports on the frame for supporting a roll of wrapping material with its 45 axis extending at an angle to the axis of the pipe, tensioning means acting on the roll to press it against the pipe, and a take-up device for regulating the tension on the roll as the wrapping material is unwound therefrom. 50

HERMAN KRAMER.
